GUN SIGHTING MEANS

John Beresky, Brooklyn, N. Y.

Application February 3, 1943, Serial No. 474,511

8 Claims. (Cl. 33—58)

This invention relates to gun sighting means of the type which are particularly designed for use with hand held and aimed guns. One object of the invention is the provision of gun sighting means which are so designed that not only does the sighting means facilitate the drawing of a bead on the target, but manipulation of the front sight to make it just embrace the target at the given range automatically effects such elevation of the rear sight as may be required at the said range to cause the bead line to intersect the trajectory of the particular gun at the target.

In my prior application Serial No. 387,995, I have shown an improvement in front sights which facilitates aiming a gun by providing adjustable stop means in said front sight that permits the front sight opening to be adjusted about the bead line from a wide open position, in which the target can quickly be viewed through the opening, to a peep sight opening during the aiming operation. I have now discovered that advantage may be taken of this adjustability of the front sight opening to adjust the rear sight to compensate for the trajectory of the gun at the range.

Since the angle which a target subtends at the eye of a gun pointer necessarily varies with the distance and in direct proportion to the distance of the target from the eye, it will be seen that if a target, of given dimensions, can just be embraced within the front sight opening of a gun, when the target is located at, say, 100 yards from the gun, then if the target be located at 200 yards from the gun the front sight opening needs to be only half as large just to embrace the target, that is, its vertical and horizontal dimensions may be reduced one-half each. Taking advantage of this fact, I have so connected the trajectory compensating elevation adjustment for the rear sight to the mechanism for effecting the operation of the stop means which determines the size of the opening in the front sight that, if the range at which the gun is to be fired gets beyond the straight part of the gun trajectory, the rear sight will be elevated sufficiently to compensate for the curve in the gun trajectory and, therefore, the bead line determined by the two sights will consistently intersect the gun trajectory at the target when the front sight has been adjusted just to embrace the target at the given range.

Although such adjustment of the rear sight is not necessary when the invention of my prior application is used at short ranges, that is, ranges within the substantially straight line part of the

gun trajectory, it is important, when the gun is to be fired at targets located at ranges that come within the curved part of the gun trajectory, that suitable compensating adjustment be made of the rear sight.

In speaking of the gun trajectory, I am referring, of course, to the trajectory of the projectile fired from the gun, which is determined to a considerable degree by the character of the ammunition. The gun trajectory can readily be determined, of course, empirically and, having once been determined and the relative movements of the sights adjusted thereto, further consideration of it will be unnecessary within useful ranges, that is ranges within which the projectile has effective striking power.

As hereinabove suggested, therefore, a general object of the present invention is so to combine with a front sight having adjustable stop means for facilitating the drawing of a bead, means whereby the manipulation of the front sight may effect such an adjustment of the rear sight, particularly at the greater ranges, as to compensate for any drop in the projectile. In other words, the invention aims so to effect such an adjustment of the rear sight in unison with the manipulation of the front sight when drawing a bead on the target that, when the front sight has been caused to embrace the outline of the target, the rear sight will have been adjusted to insure the proper gun elevation for the given range.

Other objects and important features of the invention will appear when the following description and claims are considered in connection with the accompanying drawings, in which—

Figure 1 is a plan view of a rifle of the ordinary military type such, for example, as the British Enfield rifle, having the invention embodied therein, parts being broken away;

Figure 2 is a side elevation of the structure shown in Figure 1;

Figure 3 is a section on the line 3—3 of Figure 2;

Figure 4 is a section on the line 4—4 of Figure 2;

Figure 5 is a section on the line 5—5 of Figure 3;

Figure 6 is a section on the line 6—6 of Figure 5;

Figure 7 is a view, with the cover of the casing removed, showing the stop means and the means for operating it, constituting the front sight of the gun, the stop members being in the wide open position of the sight;

Figure 8 is an enlarged view of the sighting

means shown in Figure 7 with the stop members in their peep sight adjustment, Figure 8 being a section on the line 8-8 of Figure 9;

Figure 9 is a vertical section through the front sighting means and the stop operating means on the line 9-9 of Figure 8.

As hereinabove pointed out, the front sight, which constitutes a part of the present invention, embodies in itself the invention described and claimed in my co-pending application Serial No. 387,995, filed April 11, 1941, now Patent 2,310,929, February 16, 1943. In the front sight herein shown, however, instead of using an ordinary iris shutter, such as those employed for camera stops, for reducing the front sight opening, it is found advantageous, particularly at the longer ranges, to use the finger type of stop in which the members do not entirely close the opening although they do define the peep sight.

In the illustrative front sight embodiment of the invention of my prior application Serial No. 387,995, which is incorporated in the invention of the present application, the front sight comprises a housing 2, having a front opening 4 therein of the desired maximum dimensions, this housing having a rear removable cover 6 with a hub-like extension 8 having therethrough an opening 10 of substantially the same size as the front opening 4. Pivoted upon the rear cover member 6 are the members 12 carrying the fingers 14 which define the four sides of the eventual peep sight, these fingers 14 being movable by the swinging of the members 12 about their pivots 16 in an arc-shaped path but generally radially toward the bead line at the center of the openings 4 and 10.

To effect the simultaneous movement of the fingers 14 toward their peep sight relation to each other and also into target embracing relations for different ranges, or in other words, to effect the desired adjustments between their wide open position and their peep sight positions, each member 12 is provided with a pin 18 travelling in a cam slot 20 in a rotary cam 22 carried upon the hub of a gear 24 arranged to turn in a recess 26 in the housing 2 within which the gear 24 just fits. As shown particularly in Figures 7 and 8, the housing 2 is made up of two approximately circular portions A and B which are integral with each other but which are sufficiently short of being complete circles at the point where they join so that the cam member 22 projects into the housing portion B and the gear 28 which meshes with and drives the gear 24 projects slightly into the part A of the housing. In the same manner that the gear 24 is supported in the conforming recess 26 of the part A of the housing the gear 28 fits within a substantially conforming recess 30 in the part B of the housing. This avoids the necessity for providing bearings for the hubs of these gears, which in the case of the gear 24 might interfere with the sight openings.

The housing 2, as a whole, is provided with a sleeve portion 32 adapted to fit over the front end of the rifle or other gun barrel and to be accurately positioned thereon by means of a key 34 fitting in a groove 36 in the barrel of the rifle or gun and in a groove 38 in the sleeve portion 32.

A third part C of the housing 2 has within it a circular recess 40 within which a small pinion 42, adapted to drive the gear 28 and through it the gear 24, may be located, the gear 42

being mounted upon a driving shaft 44 to which it is keyed at 46, this shaft having a front bearing 48 in an enclosing tube 50 and preferably having a further bearing in the front wall of the housing 2.

As in the case of the front sight operating means of my co-pending application Serial No. 387,995 hereinabove identified, the shaft 44 and its enclosing housing or tube 50 extend to a point within convenient reach of that hand of the gun sighter which engages the hand hold 52 of a rifle such as herein shown, or any other suitable hand hold when the invention is incorporated in other types of rifles or guns. The purpose of this, as is fully set forth in the co-pending application, is to permit the operator, while pointing the gun by means of the hand which engages the hand hold and while gradually pressing the trigger finger with his other hand, to engage suitable actuating means for turning the shaft 44 to effect the gradual movement of the fingers 14 toward the bead line through the front and rear sights, thus facilitating the sighting on the target by providing a large sight opening to start with and an approximation to a peep sight when the aim is completed and the trigger pulled.

In the illustrative embodiment of the invention, however, the movement of the fingers 14 of the front sight toward each other is utilized to control the elevation of the rear sight to compensate for any curvature there may be in the trajectory of the projectile, hereinafter referred to as the "gun trajectory," at the greater ranges.

As hereinabove pointed out, any given dimension of a target will subtend an angle at the eye which varies directly in proportion to the distance of the target from the eye. In other words, the angle which a circular target 6 inches in diameter subtends at the eye at a 100 yard range will be twice the angle which the same target subtends at the eye at a 200 yard range. If, therefore, two of the opposed fingers 14 of the stop means employed in the illustrative embodiment of the invention are brought into a position where one finger 14 merely touches the outline of the 6 inch target, as viewed therebetween, on one side while the opposed finger 14 touches the outline at a point diametrically opposite the point at which the first finger touches the outline, when the target is at a 100 yard range, the distance between these two fingers when thus adjusted will be twice the distance between the same two fingers when brought into the same relation to the same 6 inch target at the 200 yard range. Advantage is taken of this fact so to connect the means for effecting the movement of the fingers toward each other to means for varying the elevation of the rear sight hereinafter to be described that such elevation of the rear sight as is required to compensate for any drop in the travel of the projectile at the greater ranges is effected automatically. In other words, when the sights have been adjusted in the manner hereinabove set forth so that the four fingers 14 of the front sight stop means just touch the outline of a 6 inch circular target at whatever range said target is located, there will be effected automatically an adjustment of the rear sight such that the bead line through the sights will intersect the gun trajectory at the center of the target.

The illustrative means for effecting an elevation of the rear sight in unison with the adjustment of the front sight stop means, in order to

give the proper elevation of the rear sight for different ranges, comprises a pinion 54 on the shaft 44, the pinion 54, as shown in Figures 3, 4 and 5 meshing on one side directly with an intermediate pinion or gear 56 which engages the teeth of a rack 58 constituting part of one supporting rod 60 for the crossbar 62 from which the rear sight 64 is suspended. The other supporting rod 66 for the crossbar 64 is suspended. The other supporting rod 66 for the crossbar 62 is also provided with a rack 68 engaging a gear 70 which is driven from the pinion 54 through an idler pinion 72 required to cause the gear 70 to move the rack 68 in unison with the rack 58.

For ordinary short ranges, in which the gun trajectory is straight, the rear sight 64, which may be, for example, a white line on its suspended support 14, will rest upon the abutment 76. If we assume, for example, that there is no substantial curvature of the trajectory of the rifle at ranges up to 100 yards, then the fingers 14 of the stop mechanism of the front sight may be normally spaced, that is, when the stop is in its wide open position, so that they will embrace the outline of a target of a predetermined size at the 100 yard range. If the trajectory begins to curve beyond the 100 yard range, then, if a target of the same size is viewed through the front sight opening 4 at a greater range than 100 yards, it will be necessary to move the fingers 14 toward the bead line to cause their ends just to engage the viewed outline of this same target at the greater range. This will be done, as hereinabove described, by rotating the shaft 44 to drive the pinion 42 and through it the gear 28 and the gear 24.

The illustrative means for effecting the rotation of the shaft 44 for this purpose comprises push buttons 78 and 80 arranged upon opposite sides of the hand grip or hand hold 52 of the ordinary rifle so that the ordinary right handed marksman will engage the left hand push button 78 with his thumb and the right hand push button 80 with one of his fingers. The advantage of having oppositely moving stop-actuating push buttons arranged on opposite sides of the hand hold 52 is that no unusual movement of the thumb and fingers is required to effect the movement of the two push buttons 78 and 80, the action being primarily a squeezing action similar to that used to hold the rifle firmly and being an action that automatically coordinates itself with the trigger-squeezing action of the trigger finger.

Each of the push buttons is held in its outermost position by springs 82, each elongated push button being provided with two which surround hollow bosses 84 on the inside of the push buttons, said hollow bosses 84 travelling over guiding pins 86 screwed into the block 88 suspended from the gun barrel by a sleeve 90. The block 88 also provides a bearing for the shaft 44.

At the middle part of the block 88 is a slot in which a pinion 92, keyed to the shaft 44, is confined. The pinion 92 is engaged by two racks, the upper rack 94 being connected to the right hand push button 80 and the lower rack 96 being connected to the left hand push button 78. It will be seen, therefore, that when the push buttons 78 and 80 are pushed inwardly as when aiming the gun, the shaft 44 will be rotated, by engagement of the racks 94, 96, with the pinion 92, in a direction to cause the pinion 42 to rotate the cam 22, through the gears 24 and 28, in the direction to cause the fingers 14 to move inwardly

toward each other. When the push buttons 78 and 80 are released the springs 82 move them outwardly to rotate the shaft 44 in the opposite direction and thus cause the fingers 14 to separate and enlarge the stop opening in the front sight to its maximum size.

These same rotations of the shaft will cause first a lifting of the rods 60 and 66 by the racks 58 and 68 and then a lowering thereof.

- 10 If, as above suggested, the rear sight 64, when resting on the abutment 76 is at the right elevation to draw bead on a target located at a range within the straight line part of the gun's trajectory, it will only be necessary to raise the sight 15 64 when the target is at a range that is within the curved part of the gun's trajectory. This can readily be determined empirically and the adjustable stop members 98 and 100 on the rods 60 and 66 can then be so adjusted that they will 20 pick up the crossbar 62 and through it lift the rear sight 64 sufficiently to compensate for the curvature of the gun's trajectory when the fingers 14 are brought into outline-embracing relation to the target of the predetermined size at the greater range.

Two such positions of the rear sight are shown in Figures 3 and 4, Figure 3 showing the sight set for a range within the straight line part of the gun trajectory, the stops 98 and 100 being below 30 the crossbar 62. In Figure 4 the target of the predetermined size is at a range that comes within the curved part of the gun trajectory and therefore, in rotating the shaft 44 in the direction to move the fingers 14 into outline-embracing 35 relation to the target at the greater range, the rods 60 and 66 have been elevated through the racks 58 and 68 sufficiently to move the adjustable stop members 98 and 100 upward until they have picked up the crossbar 62 and carried 40 the rear sight 64 to an elevation above the abutment 76 sufficient to compensate for the drop in the trajectory at the greater range or, in other words, so that the bead line through the rear and front sights will intersect the trajectory at 45 the target at the greater range.

From the foregoing description it will be seen that as an incident to the sighting of the gun on the target and the movement of the fingers 14 of the front sight stop toward the bead line, an automatic elevation of the rear sight 64 is effected sufficient to compensate for the curvature of the trajectory of the projectile at the greater range. It is therefore not necessary for the gun pointer to estimate the range and set 50 an elevation gauge as in ordinary gun sighting. As herein shown, however, elevation readings may be provided on the guides 102 and 104 for the crossbar 62 from which, if the gun pointer so desires, he may read the range determined by the setting of the fingers 14 just to engage the outline of the target of the predetermined dimension.

Reference has been made hereinabove to a circular target 6 inches in diameter at the 100 yard 55 range as a suitable setting target. One reason for this is that this corresponds approximately to the size of the face of the ordinary man as he is viewed through the sights of a military rifle, and similar areas can readily be estimated on other 60 types of targets. Thus the gun pointer can bring the fingers 14 of his front sight into outline-embracing relation to an area corresponding to a 6 inch circular target on almost any type of target at almost any practicable range for open sight 65 work, thus quickly setting his sights to the range,

with the resultant securing of effective aiming. It will be noted that the illustrative rifle is provided with the usual wind drift gauge comprising a member 106 carrying the sight and arranged to be swung about 108 by a worm provided with an operating head 110. The guides 102 and 104 are so connected to the member 106 that they swing bodily to the right or to the left to compensate for the force of the wind when adjustment is made by means of the knurled head 110. To permit such bodily movement of the guides without interfering with the operation of the elevating mechanism, it will be noted that the rods 60 and 66 do not necessarily contact the upper guide rolls 112 but permit some swinging movement of the rods in either direction to permit them to follow the adjustments of the wind drift gauge.

Although the invention has been described in connection with its embodiment in a hand held and aimed gun, it will be understood that its broad principles are applicable to other types of guns such as machine guns, and that the means for controlling the opening of the front sight could also be embodied in other types of sights than that herein shown.

What is claimed as new is:

1. Gun sighting means comprising a front sight having stop members arranged to converge toward a point in the bead line from the rear sight to a target whereby they may be caused to embrace the outline of a target of given dimension as viewed through said front sight at different ranges, a rear sight movable vertically to insure proper elevation of the gun for different ranges and operating connections between said stop members of said front sight and said vertically movable rear sight so intergeared that, when the front sight has been caused to embrace the outline of the target, the rear sight will have been adjusted to insure the proper gun elevation for the given range.

2. In gun sighting means, a front sight, including stop members movable toward a common center to embrace the outline of a target of given dimensions as viewed through the sight, means for setting said front sight to a normal open position in which said stop members will embrace the outline of a given target as viewed through the sight at a predetermined short range, an elevatable rear sight and operating connections between said front and rear sights, including actuating means constructed and arranged to be carried by the gun in manually operable proximity to a hand hold of the gun pointer when sighting the gun on the target, for moving said stop members into embracing relation to the target outline at increased ranges and simultaneously effecting such elevation of the rear sight as is required to cause the bead line through the sights to intersect the gun trajectory at each range.

3. In gun sighting means, a front sight comprising stop means adjustable to a normal setting adapted just to embrace within the stopped

opening a given target at a predetermined range, stop operating means for reducing the dimensions of said stop opening to make it just embrace said target at greater ranges, an elevatable rear sight, means for effecting elevating movement thereof, and operating connections between said stop operating means and said rear sight elevating means, including actuating means therefor constructed and arranged to be carried by said gun in manually operable proximity to a hand hold of the gun pointer, when sighting the gun on the target, for effecting the operative movements of said stop means and of said elevating means in such timed relation to each other that reduction of the stop opening, during the aiming operation, to a size that will just embrace the target at a greater range, will effect, in unison therewith, such elevation of the rear sight as is required to cause the bead line through the sights to intersect the gun trajectory at the said range.

4. Gun sighting means for use with a gun provided with a rear sight, said means comprising a front sight having therein a normal full sight opening about the bead line from the rear sight to a target, stop members movable into said opening to define a target-embracing peep sight about said bead line, and means for effecting said movement of said members, said means including push buttons located on opposite sides of a hand hold of the gun in position for convenient manipulation by a thumb and a finger of the gun-aiming hand of the gun pointer, and operating connections between said push buttons and said stop members whereby movement of said push buttons toward each other during the gun pointing operation effects the desired movement of said stop members into target-embracing relation to each other.

5. Gun sighting means according to claim 4 in which the stop members are in the form of fingers arranged to leave a part of the normal opening unobstructed as they move into their peep sight defining relation to each other.

6. Gun sighting means according to claim 4 having an elevatable rear sight and operating connections between said push buttons and said rear sight for effecting an elevation thereof proportional to the movement of the stop members toward each other.

7. Gun sighting means according to claim 4 in which springs and abutments therefor are provided, said springs being arranged to act against the push buttons in their movement to effect the peep sight defining movement of the stop members, whereby they are tensioned to effect the restoration of the push buttons and, therewith, the stop members to their initial positions upon release of said push buttons by the gun pointer.

8. Gun sighting means according to claim 1 in which a laterally adjustable support for said rear sight is mounted on said gun, whereby provision is made for bodily lateral movement of the rear sight to compensate for wind drift.

JOHN BERESKY.
